PORTRABLE COMBINATION INTERNAL COMBUSTION ENGINE AND ELECTRIC STARTER

Joseph R. Harkness, Germantown, Wis., assignor to
Briggs & Stratton Corporation, Milwaukee, Wis., a
corporation of Delaware

Filed Aug. 26, 1968, Ser. No. 13,282

Term of patent 14 years

Int. Cl. D15—01

U.S. Cl. D77—1

Fig. 1.

Fig. 2.

Fig. 3.

FIGURE 1 is a perspective view of a portable combination internal combustion engine and electric starter embodying my new design;

FIGURE 2 is a perspective view from the other side thereof; and

FIGURE 3 is a top plan view thereof.

The dominant features of my design reside in those portions thereof shown in solid lines.

I claim:

The ornamental design for a portable combination internal combustion engine and electric starter, as shown and described.
